 Claims priority, application Netherlands, Nov. 23, 1957,
 222,701; Apr. 13, 1957, 216,318
 12 Claims. (Cl. 167—65)

The instant application is a continuation-in-part of applicants' co-pending application Serial No. 280,784 filed May 16, 1963, which application is a continuation-in-part of application Serial No. 773,763 filed November 13, 1958, and now abandoned, and application Serial No. 802,677 filed March 30, 1959, now abandoned; said Serial No. 802,677 being a continuation-in-part of application Serial No. 727,394, filed April 9, 1958, and now abandoned.

The instant invention relates to a new and novel method of relieving spastic conditions in the human being and to a novel pharmaceutical composition useful therefor.

In the treatment of spastic conditions occurring because of functional or organic disorders, it has long been an object of medical research to provide a method that would affect only the target areas and have little or no side effect. Particularly in the treatment of gastrointestinal spasms, a method which would effectively reduce the spasms yet have little or no side effects is highly desirable.

However, until now, such drugs that were available have displayed certain undesired side effects. Thus, many of these drugs show atropine-like side effects resulting in dried mouth, blurred vision, inhibition of salivary secretion and retention or secretion of gastric acid.

Further, other drugs of the papaverine type which have been employed frequently, cause complete paralysis of normal peristaltic activity.

A principal object therefore, is to provide a method of relieving spastic conditions of the colon in human beings while inducing little or no side-effects.

This and other objects of our invention will be evident from the description that follows:

According to our invention, we have found that the administration of the compound 4-[N-ethyl-1'-methyl-2''-(4''-methoxy-phenyl) - ethylamino] - butyl-3,4 - dimethoxy benzoate, called hereinafter mebeverine, its non-toxic pharmaceutically acceptable acid addition salts, particularly in the form of its hydrochloride provides a particular useful method of reducing such spasms in human beings thereby eliminating or materially reducing the intensity of the associated pain. Other pharmaceutically acceptable salts such as the phosphate, bromide, acetate, tartrate and benzoate may also be employed.

Thus mebeverine is particularly useful for the treatment of primary (essential) irritable colon syndrome i.e. spastic colitis and secondary irritable colon syndrome. Among the secondary colon irritable syndromes that may be treated are those due to gall bladder affections such as biliary dyskinesia and gall stones, diverticulosis, diverticulitis coli enteritis regionalis, enteritis, dysentery, ulcerus ventriculi, duodenal ulcer, and diseases of the urinary tract such as renal calculi.

In cases of spasms which are accompanied by pain of high intensity such as those due to gall stones or renal calculi, an analgesic drug such as dipyrone "Novalgin

(e)" (sodium 1-phenyl-2,3-dimethyl-5-pyrazolone - 4-methylaminomethane-sulfonate), phenyl - butazone or meperidine hydrochloride "Demeral" hydrochloride should be included with the mebeverine.

5 In all cases, a sedative such as phenobarbital or a tranquilizer such as fluphenazine hydrochloride "Prolixin," prochloroperazine "Compazine," maprobamate and chlorodiazepoxide hydrochloride "Librium" may also be included.

10 The daily dosage of mebeverine is for an adult 200-400 mg., for a child (1-12 years) 50-250 mg. and for an infant up to 12 months less than 50 mg. Equivalent amounts of its non-toxic acid addition salts may be used.

15 The mebeverine may be administered orally in tablet or liquid form, by suppositories or parenterally by intramuscular injection.

20 The tablets and suppositories each contain from 20 to 100 mg. of mebeverine. The ampules for injection contain from 10 to 50 mg. of mebeverine per ml. The syrup contains from 4 to 20 mg. of mebeverine per cc.

25 The mebeverine may be prepared according to the method disclosed in our pending United States patent application Serial No. 280,784, filed May 16, 1963, of which the instant case is a continuation-in-part.

Our invention will now be described with greater detail with references to the following examples:

20 Examples of suitable pharmaceutical formulations of mebeverine are as follows.

30	I. Coated tablets—	
35	a. Kernel	Mg./tablet
	Mebeverine hydrochloride	50
	Lactose	10
	Polyvinyl Pyrrolidone	0.5
	Formaldehyde-caseine	4.5
	Carboxymethylcellulose	4
	Magnesium stearate	1
40	b. Coating:	
45	Talc	15
	Sugar (crystal)	54.5
	Starch (potato)	0.5
	Carnauba wax	0.02
	Shellac wax	0.02
	Dammar resin	0.03
50	II. Ampules—	
	Mebeverine HCl	50
	Benzyl alcohol	15
	Distd. water ad 1 ml.	
55	III. Suppository—	
	Mebeverine	100
	Tert. calcium phosphate	350
	Sugar (powdered)	350
	Starch (corn)	350
60	Talc	40
	Magnesium stearate	10
		1200
65	Massupol *	400

* Massupol: See Merck Index, 7th ed., p. 638.

70 The mebeverine HCl tert. calcium phosphate, sugar and starch are sieved (40 mesh), moistened with ethanol/water (50/50). The mass is granulated, dried 5 hours at 50° C. and mixed with the talc and magnesium-stearate. From this mixture tablets are formed and coated at 40° C. with the molten massupol.

IV. Coated tablets: Mebeverine + Novalgine¹ (Novalgin) or sodium novaminesulfonate—

a. Kernel: Mg./tablet

Mebeverine	50
Sodium novaminesulfonate	250
Powdered sugar	50
Starch (potato)	25
Gelatin	2
Formaldehyde-casine	10
Talc	33
Magnesium stearate	33
Dstd. water, ± 1 liter/100,000 tablets.	
Ethanol 96% v/v. (denat.), ± 1 liter/100,000 tablets.	15

b. Coating:

Talc	98.1
Sugar (crystal)	367.7
Arab. gum	3.15
Galatine	3.15
Titanium dioxide	2.9
Shellac wax	0.12
Carnauba wax	0.12
Dammar resin	0.2
Carbon tetrachloride, 2.4	1/1,000,000
tablets.	
Dstd. water, ± 10 l/100,000 tablets.	

¹ "Novalgine"—sodium salt of 1-fenyl-2,3-dimethyl-pyrazolone-(5)-4-methylaminomethane-sulfonic acid.

V. Ampules mebeverine + Novalgine—

Mebeverine	20
Sodium novaminesulfonate	500
Dstd. water, ad 1 ml.	

VI. Suppository mebeverine + Novalgine—

Mebeverine.HCl	100
Sodium novaminesulfonate	1000
Vehicle x	2150

x Vehicle: neutral fat, prepared from vegetable oils.

Melting point: 36-37° C.
Solidification point: 31-33° C.
Saponification value: 215-225
Iodine value: 1.0
Acid value: 0.5

VII. Coated tablets mebeverine + phenobarbital—

a. Kernel: Mg./tablet	45
Mebeverine.HCl	50.0
Phenobarbital	10.0
Polyvinylpyrrolidone	0.5
Formaldehyde-casine	4.5
Carboxymethylcellulose MZ 851	4.0
Magnesium stearate	1.0
Ethanol abs. (denat.), ± 4.5 liter/1,000,000 tablets.	50

b. Coating:

See Example 1

Illustrative examples employing mebeverine are shown in the following table and examples:

TABLE

Case No.	Age in years	Sex	Diagnosis	Daily dose	Duration of treatment in days	Effect	Undesirable side effects
1—R.E.	68	m	Spastic colitis	6 coated tablets	36	Excellent	None
2—B.G.B.	13	m	Gastric spasms	2 coated tablets	11	do	Do.
3—F.A.	55	m	Gastroduodenitis, cirrhosis of liver.	4 coated tablets	26	Good	Do.
4—R.F.	25	f	Polyserositis, colic pains in abdomen.	1 ampule (compositum).	1	Excellent	Do.
5—V.G.	34	f	Adnexitis.	do	1	Slight	Do.
6—F.M.	63	f	Hepatic colic, cholecystitis with lithiasis.	3 ampules (compositum).	2	Excellent	Do.
7—T.F.	63	m	Neoplastic schalasia of the oesophagus.	2 ampules	9	Good	Do.

Each coated tablet contains 50 mg. mebeverine hydrochloride.

Each ampule contains 100 mg. mebeverine hydrochloride.

Each ampule (compositum) contains 100 mg. of mebeverine hydrochloride and 2.5 g. of "Novalgin."

Example

$\frac{1}{4}$ tablet (50 mg. of mebeverine hydrochloride in each tablet) were administered three times a day to 6 infants of 4-6 weeks for a period of three weeks. All of these infants were suffering from aerophagy or meteorism. In three cases, a pronounced mitigation of the colic attack was achieved. In the other three cases, the colic attacks ceased only during the administration of the mebeverine hydrochloride.

While we have described our invention in connection with specific embodiments and applications, other modifications thereof will be readily apparent to those skilled in this art without departing from the spirit and scope of the invention as defined in the appended claims.

What we claim is:

1. A method of treating spastic conditions of the colon in a human comprising administering to said human a member selected from the group consisting of the base 4' - [N - ethyl - 1" - methyl - 2" - (4''' - methoxy - phenyl) - ethylamino] - butyl - 3,4 - dimethoxy benzoate and its non-toxic pharmaceutically acceptable acid addition salts.

2. A method of treating spastic conditions of the colon in a human comprising orally administering to said human a member selected from the group consisting of the base 4' - [N - ethyl-1"-methyl-2"-(4'''-methoxy-phenyl)-ethylamino]-butyl-3,4-dimethoxy benzoate and its non-toxic pharmaceutically acceptable acid addition salts.

3. A method of treating spastic conditions of the colon in a human comprising parenterally administering to said human a member selected from the group consisting of the base 4' - [N-ethyl-1"-methyl-2"-(4'''-methoxy-phenyl)-ethylamino]-butyl-3,4-dimethoxy benzoate and its non-toxic pharmaceutically acceptable acid addition salts.

4. The method of claim 1 wherein the hydrochloride salt is employed.

5. The method of claim 1 wherein 200-400 mg. of the base or an equivalent amount of the salt is administered daily to a human adult.

6. The method of claim 1 wherein 50-250 mg. of the base or the equivalent amount of the salt is administered daily to a human being.

7. The method of claim 1 wherein up to 50 mg. of the base or an equivalent amount of the salt is administered daily to a human infant.

8. A method of treating spastic conditions of the colon in a human comprising administering to said human a member selected from the group consisting of the base 4' - [N - ethyl - 1" - methyl - 2" - (4''' - methoxy - phenyl) - ethylamino] - butyl - 3,4 - dimethoxy benzoate and its non-toxic pharmaceutically acceptable acid addition salts.

its non-toxic pharmaceutically acceptable acid addition salts together with an analgesic drug.

9. A method of treating spastic conditions of the colon in a human comprising administering to said human a member selected from the group consisting of the base 4' - [N - ethyl - 1" - methyl - 2" - (4'" - methoxy-phenyl) - ethylamino] - butyl - 3,4 - dimethoxy benzoate and its non-toxic pharmaceutically acceptable acid addition salts together with dipyrone.

10. An antispasmodic composition particularly adapted for treating spastic conditions in colons in humans comprising in an antispasmodically effected amount, a member selected from the group consisting of the base 4' - [N - ethyl - 1" - methyl - 2" - (4'" - methoxy-phenyl) - ethylamino] - butyl - 3,4 - dimethoxy benzoate and the pharmaceutically acceptable acid addition salts thereof and a major amount of a pharmaceutical carrier therefor.

11. An antispasmodic composition particularly adapted for treating spastic conditions of the colon in humans comprising in an antispasmodically effective amount, 4' - [N - ethyl - 1" - methyl - 2" - (4'" - methoxy-phenyl) - ethylamino] - butyl - 3,4 - dimethoxy benzoate hydrochloride, and a major amount of a pharmaceutical carrier therefor.

12. An antispasmodic composition particularly adapted for treating spastic conditions of the colon in humans comprising in an antispasmodically effective amount, 4' - [N - ethyl - 1" - methyl - 2" - (4'" - methoxy-phenyl) - ethylamino] - butyl - 3,4 - dimethoxy benzoate hydrochloride, dipyrone and a major amount of a pharmaceutical carrier therefor.
